UNITED STATES PATENT OFFICE.

MALCOLM L. COSSITT, OF OAKLAND, CALIFORNIA, ASSIGNOR TO MANIFOLD IMPRESSIONS CORPORATION, OF CARSON CITY, NEVADA, A CORPORATION OF NEVADA.

MANIFOLDING ATTACHMENT FOR TYPEWRITERS.

Application filed August 21, 1923. Serial No. 658,640.

To all whom it may concern:

Be it known that I, MALCOLM L. COSSITT, a citizen of the United States, residing at Oakland, in the county of Alameda and State of California, have invented certain new and useful Improvements in Manifolding Attachments for Typewriters, of which the following is a specification.

My invention relates to that class of manifolding attachments for typewriters in which a plurality of manifolding members are carried by movable arms mounted on the machine and are adapted to be placed in and removed from functional position in the line of type impact.

One of the objects of my invention is to provide simple and effective means for selectively operating the carrying arms whereby one or more of the manifolding members may be used as required.

Another object is to provide means for adjusting the position of the paper-holding fingers to avoid interference with the manifolding members when the latter are being moved to functional position. Other objects are to improve the mounting of the movable arms, to provide simple means for holding said arms at the limits of their movement both in and out of position, and to provide for oscillating the manifolding members when in functional position, to utilize their full width. To these ends my invention consists in the novel manifolding attachment for typewriters which I shall hereinafter fully describe by reference to the accompanying drawings, in which—

Fig. 1 is a front elevation of my manifolding attachment as applied to a typewriter.

Fig. 2 is a plan view partly in horizontal section of the arm-operating selective assembly, taken on the line 2—2 of Fig. 3, said view being from the rear of the attachment at the right hand of Fig. 1.

Fig. 3 is a part sectional view of the same on the line 3—3 of Fig. 2.

Fig. 4 is an elevation of the rotatable arm-operating selective member showing its independently operatable pawl missing the shorter lug 15' of the second arm 15 and engaging the longer lug 12' of the first arm 12.

Fig. 5 is a perspective view, enlarged, of the arm-operating selective member and its independently operatable pawl.

Fig. 6 is a perspective view, enlarged, of the first arm 12 with its axis sleeve and its long lug.

Fig. 7 is a perspective view, enlarged, of the second arm 15 with its axis rod and its short lug.

Fig. 8 is a section on the line 8—9 of Fig. 4, in the direction of the arrow, showing normal upright position of the arms.

Fig. 9 is a section on the same line 8—9 of Fig. 4, but showing the first arm moved down.

Fig. 10 is a detail elevation of the arm-operating selective member, similar to Fig. 4, but showing the parts in normal position prior to movement.

Fig. 11 is a plan view of the arm-operating selective assembly, showing its bracket mounting on the back bar 2' of the machine.

Fig. 12 is a right hand end view enlarged of my attachment, the turning knobs being omitted.

Fig. 13 is a rear elevation of the arm-operating assembly and its mounting.

Fig. 14 is a section on the line 14—14 of Fig. 11.

Fig. 15 is a section on the line 15—15 of Fig. 11.

Fig. 16 is a left-hand end view, enlarged, of my attachment on the line 16—16 of Fig. 17.

Fig. 17 is a plan view of the left hand end.

Fig. 18 is a detail showing the sequence of the ribbons with respect to the platen and the record paper sheets.

Fig. 19 is a view of a means for adjusting automatically the paper-fingers.

1 is a portion of the frame of a typewriter, 2 is the platen-carriage, 3 is the platen, the shaft 4 of which carries the turning knob 5.

6 is the index pointer, 7 is the main inking ribbon, 8 are the paper-fingers at the front of the platen near each end, and 9 in Fig. 12 is the paper guide apron. These or similar elements are all parts of a typical typewriter and are sufficient for a full understanding of my intention. 10 in Figs. 12, 13, and 16, are brackets having angularly directed feet 10' by which they are secured to a back bar 2' on the platen carriage 2. There are 2 brackets 10, one at either end of the platen carriage, said brackets rising back of the platen and paper guide apron, Figs. 12 and 16. In the brackets and extending between them is rotatably mounted 110

a rod 11 which has fixed to it near each end an arm 15 between the extremities of which is carried a manifolding member 16 here shown as a short section of ribbon Figs. 1 and 18. Upon the rod 11 is rotatably mounted a sleeve 14 which has fixed to it near each end an arm 12, between the extremities of which is carried a second manifolding member or ribbon 13, Figs. 1 and 18. The adjacent arms 12 and 15 of each pair lie in nested relation for a portion of their length, as seen in Figs. 12 and 16, the arms 12 being the innermost.

The arm 12 at the right hand, viewed from the front of the machine has near the front of its base a laterally projecting lug 12', Fig. 6, and the corresponding arm 15 has at its base near its front a laterally projecting lug 15', Fig. 7. The lug 15' lies back of and is shorter than the lug 12' the two lugs lying in a circular path having the rod 11 for a center. It will now be seen that if pressure from behind be brought to bear upon the lug 12' the pair of arms 12 will be turned with their sleeve 14 about the rod 11 as an axis, from an elevated position back of and above the platen as seen by the dotted lines in Fig. 12 to a depressed position down to and curving over the platen, as shown by the full lines in said Fig. 12, thereby carrying their manifolding member 13 down to functional position in front of the platen in the line of type-impact, between the record paper sheets 43 as in Fig. 18. If then pressure from behind be exerted upon the lug 15', the pair of arms 15 with their manifolding member 16, Fig. 18, will be similarly operated turning with their rod 11 as an axis, said operations being those common to manifolding attachments of this type. And it will also be seen that if, when said arms are in depressed position, pressure be brought upon the front of the lug 12', tending to lift the arms 12, both sets of arms 12 and 15 will be raised to elevated position, since the arms 12 underlie the arms 15.

Referring now particularly to Fig. 2, there is mounted rotatably about the projecting end of the rod 11 and within the bearing of the right hand bracket 10 a short sleeve 17 having a turning knob 18 upon its end. Upon this sleeve 17 is slotted and pin-guided at 19 an arm-operating member 20, adapted for turning movement with and reciprocal linear movement on said sleeve, the latter movement being controlled by a spring 21 tending to hold said member projected towards the ribbon carrying arms 12 and 15, as seen in Figs. 2 and 3. In a longitudinal slot in the inner end of the arm-operating member is slidably mounted a pawl 22 the point of which projects into the circular path in which the arm lugs 12' and 15' lie and move, Fig. 2. The operative end 65 of the arm-operating member 20 is formed,

forward of the pawl 22, with a cam incline 20' and this incline lies in the path of the longer lug 12' but misses the shorter lug 15', Figs. 2 and 10. It will be well now to describe the operation and effect of the arm operating member and its pawl. Assume both arms 12 and 15 to be in an elevated position as seen in Fig. 16, and in dotted lines in Fig. 12. Under the influence of the spring 21, the arm-operating member 20 is held forward with its cam incline 20' in the path of the longer lug 12' and its slideable pawl 22 in the path of the shorter lug 15' as seen in Figs. 2 and 10. When the short sleeve 17 is turned forward by its knob 18, 80 the member 20 turns with it. But when the cam incline 20' of said member reaches and contacts with the longer lug 12' said member 20 is thereby linearly forced back, and it carries the pawl 22, which it should be stated is seated with sufficient friction, back with it, so that the point of the pawl misses the short lug 15', and then engages and picks up the long lug 12' as seen in Fig. 4; and further rotative movement then carries the first 90 pair of arms 12 down, as heretofore described. See Fig. 9. A reverse turning of the knob 18 then carries the member 20 and its pawl 22 back and said member, under the influence of the spring 21, moves forwardly, 95 the pawl 22 slipping by and engaging behind the short lug 15'. Forward turning of the knob 18 now causes the pawl by contact with said short lug 15' to carry down the second pair of arms 15, the member 20 remaining projected since it is free at first, of the coaction of its cam incline 20' and the depressed long lug 12'. But towards the end of this second stroke of the member 20 and before the second pair of arms 15 are 105 fully down, the cam incline 20' of said member reaches the depressed long lug 12' so that said member begins to move back which would normally have the effect of carrying the pawl 22 back with it away from the short 110 lug 15' and this would result in a failure to depress the second pair of arms 15 to their limit. To avoid this is the purpose of the separately controllable pawl 22, the further 115 control features of which are as follows.

Rotatably mounted about the arm-operating member 20 is an outer bearing 23 in which is made an arcuate guide slot 23' the outer wall of which near its lower end is inclined at 23'' towards the inner wall. See 120 Figs. 4 and 10. The pawl 22 is provided with a stud 22' which plays in this slot 23' both circularly and linearly. Its normal play is against the inner wall of the slot as in Fig. 10, while its linear play is between 125 the inner and outer walls of said slot. The general width of the slot is such as to provide for the backward movement of the member 20 under the contact of its cam-incline 20' with the long lug 12', but when the 130

stud 22' of the pawl 22 reaches the incline 23" of the outer wall of the guide slot 23' the pawl is stopped from moving back with the member 20 which at the time is thus moving, its cam incline 20' now being in contact with and acted upon by the previously depressed long lug 12'. The pawl 22 therefore does not withdraw from its contact with the short lug 15' but continues to engage it and to depress it to its limit, so that the second pair of arms 15 can be fully depressed.

In order to more fully understand the reason for and the function of the separately controllable pawl 22 of the present arm-operating selective member and to point out clearly the novelty herein which novelty rests in said pawl, it may be of advantage to refer to my previous Patent No. 1,452,193, dated April 17, 1923, which discloses an arm-operating selective mechanism similar in general to the present mechanism, in that the previous device comprises a linearly movable arm-operating member rotatable in the axis of movement of the arms, and provided with a pick-up shoulder adapted to selectively engage lugs of different lengths upon the arms, the selection being controlled by cam inclines on said member. In that device, however, the pick-up shoulder is integral with said arm-operating member, and, therefore, when, upon the second stroke, said member is incidentally forced back near the limit of the stroke the pick-up shoulder tends to withdraw from the shorter arm-lug it is then engaging, with the result that the second pair of arms do not quite reach their limit of depression. It will now be seen that this difficulty is, by the present invention, overcome, due to the separately controllable pawl 22 carried by the arm-operating member 20.

To return the arms to elevated position the member 20 is formed with a shoulder 24, Fig. 5, which rises up under the longer lug 12' of the arm 12.

The outer bearing 23, heretofore referred to is extended at 25, Figs. 2 and 11, for three purposes. One purpose is to provide a longer journal bearing for the ends of the axis members 11 and 14 of the arms 15 and 12, to counteract the torsional strain upon them due to the off-center contact pressure of the pawl 22 on the arm lugs 12' and 15'. Another purpose is to carry the yielding locking springs 26 and 27, the former bearing upon flattened places 28 which are 45 degrees apart, on the rod 11 Fig. 15 and the latter bearing upon flattened places 29 on the sleeve 14, Fig. 14, so that the arms 12 and 15 are yieldably held or locked at their limits of movement. A third purpose is to carry the lever 30, Figs. 2, 11 and 12, for adjusting the manifolding ribbons width-wise when in functional position, at each

line spacing movement of the platen, so that said ribbons may be utilized over practically their entire width, thereby prolonging their life. The lever 30 is secured at one end to the rocking outer bearing 23 and at its other end it is yoked upon a cam 31, Fig. 12 on the platen shaft 4. When the ribbon carrying arms are depressed to functional position, the locking springs 26 and 27 being in engagement with the flattened places 28 and 29 on the axis members 11 and 14 of said arms, frictionally connect the outer bearing 23 with said members. Then when the platen is rotated, its shaft cam 31 rocks the lever 30 together with the outer bearing 23; and thus through the springs 26 and 27 which said bearing carries, the axis members 11 and 14 are rocked, which movement will oscillate the ribbon carrying arms and the ribbons transversely of the platen. The paper fingers 8 in front of the platen, near each end are as usual yieldably held close to the platen and are slidable to different positions along the length of the platen. On account of their necessary closeness to the platen, it is obvious that some means must be provided to temporarily move them away from the platen, in order to allow the manifolding ribbons 13 and 16 to freely pass in between them and the platen, in descending to their functional position in the line of type impact. Accordingly I have substituted for the usual fixed bar or rod which carries these paper fingers 8 a rocking bar 32, Figs. 16 and 17, held under rotative tension by a spring 33 at one end. The paper fingers are slidably mounted upon this bar and rock with it. One end of the bar 32 has a crank 34, and against this bears a pivoted finger-lever 35, by the operation of which, the bar 32 may easily be rocked to carry the paper fingers 8 outwardly away from the platen, as shown by the dotted lines in Fig. 16, while the manifolding ribbons are descending to place. Thereupon the lever 35 being released the bar 32 will rock back, under the influence of its spring 33, and carry the paper-fingers back to functional position. Although this opening of the paper fingers may be performed by manual operation of the finger-lever 35, it may, if found desirable, be effected automatically through the movement of the ribbon carrying arm itself. I illustrate such automatic operation in Fig. 19 wherein the upper end of the lever 35 is connected by a link 36 with one of the ribbon arms 15. The connection of the link and lever is by means of a stud 37 on the link, playing in an elongated slot 38 in the head of the lever, said slot having an initial socket 39 in which the stud normally bears. It will be seen that as the arm 15 moves forward, the stud 37 bearing on the socket 39 will throw the lever 35 forward and thus rock

the paper-finger bar 32. Then when the arm 15 is depressed to its limit and remains there, the link 36 may be manually moved to release the engagement of the stud 37 and socket 39, whereupon the lever may travel back with its head slot 38 playing over the stud, thus allowing the arm 15 to remain depressed while the paper-finger bar 32 rocks back.

19 In Figs. 1 and 16, are shown the usual ratchet mechanism for turning the platen, comprising the lever 40, the pawl 41 and the ratchet 42.

I claim:

15 1. A manifolding attachment for typewriters comprising a rotatable member mounted on the machine; a plurality of independently movable pairs of spaced arms; a manifolding member carried by each pair 20 of arms and adapted by the movement of said arms to be placed in and removed from functional position in the line of type impact; an arm-operating member fitted upon said rotatable member for rotation therewith and for linear movement thereon; 25 means for controlling the linear movement of said arm-operating member; and coacting devices on said arm-operating member and said arms for independently selectively moving each pair of arms about their pivotal centers by the rotation of the rotatable member, consisting of lugs of graduated length on the arms, an independently controllable pawl carried by said arm-operating member, 30 and a cam on said member to selectively determine the contact of said pawl with said length-graduated arm-lugs.

2. A manifolding attachment for typewriters comprising a rotatable member 40 mounted on the machine; a plurality of independently movable pairs of spaced arms; a manifolding member carried by each pair of arms and adapted by the movement of said arms to be placed in and removed from functional position in the line of type impact; an arm-operating member fitted upon said rotatable member for rotation therewith and for linear movement thereon; 45 means for controlling the linear movement of said arm-operating member; and coacting devices on said arm-operating member and said arms for independently selectively moving each pair of arms about their pivotal centers by the rotation of the rotatable member, consisting of lugs of graduated length on the arms, a pawl carried by said arm-operating member for rotation therewith and independent linear movement thereon, means for controlling the independent linear movement of the pawl to define its projection from said arm-operating member, and a cam on said arm-operating member to selectively determine the contact of said pawl with said length-graduated 55 arm-lugs.

3. A manifolding attachment for typewriters comprising a rotatable member mounted on the machine; a plurality of independently movable pairs of spaced arms; a manifolding member carried by each pair of arms and adapted by the movement of said arms to be placed in and removed from functional position in the line of type impact; an arm-operating member fitted upon said rotatable member for rotation therewith and for linear movement thereon; 75 means for controlling the linear movement of said arm-operating member; and coacting devices on said arm-operating member and said arms for independently selectively moving each pair of arms about their pivotal centers by the rotation of the rotatable member, consisting of lugs of graduated length on the arms, a pawl carried by said arm-operating member for rotation therewith and independent linear movement thereon, said pawl having a controlling stud, an outer bearing about said arm-operating member having a cam slot in which the stud of pawl plays, to control the independent linear 80 movement of the pawl, and a cam on said arm-operating member to selectively determine the contact of said pawl with said length-graduated arm-lugs.

4. A manifolding attachment for typewriters having a platen, comprising a plurality of independently rotatable concentric members each carrying a pair of spaced arms, a manifolding member carried by each pair of arms and adapted by the rotation 95 of the concentric members to be placed in and removed from functional position in the line of type-impact; a sleeve independently rotatable about the axis of said concentric members; an arm-operating member fitted upon said sleeve for rotation therewith and for linear movement thereon; means for controlling the linear movement of said arm-operating member; coacting devices on said arm operating member and said arms 100 for independently selectively moving each pair of arms by the rotation of said sleeve; an outer bearing independently rotatable about said arm-operating member; means carried by said outer bearing and acting 105 on the rotatable concentric members to yieldingly hold the manifolding members at the limits of their movement; a lever carried by said outer bearing to oscillate it, and a cam associated with the platen for oscillating said lever.

5. A manifolding attachment for typewriters comprising a pair of spaced arms mounted for movement upon the machine; a manifolding member carried by said arms and adapted by their movement to be placed in and removed from functional position in the line of type-impact; paper-fingers associated with the machine platen and lying in the path of the manifolding member; and 125

means adapted to move said fingers to clear the path of said manifolding member simultaneously with the movement of said member.

- 5 6. A manifolding attachment for typewriters comprising a pair of spaced arms mounted for movement upon the machine; a manifolding member carried by said arms and adapted by their movement to be placed
10 in and removed from functional position in the line of type-impact; paper-fingers associated with the machine platen and lying in the path of the manifolding member; a rocking bar carrying said fingers and adapted
15 to move them to and from the platen to clear the path of said manifolding member; and means dependent upon the movement of said arms for rocking said bar.

7. A manifolding attachment for type-

writers comprising a pair of spaced arms 20 mounted for movement upon the machine; a manifolding member carried by said arms and adapted by their movement to be placed in and removed from functional position in the line of type-impact; paper-fingers 25 associated with the machine platen and lying in the path of the manifolding member; a rocking bar carrying said fingers and adapted to move them to and from the platen to clear the path of said manifolding 30 member; and means, dependent upon the movement of said arms in carrying the manifolding member to functional position, for rocking said bar.

In testimony whereof I have signed my name to this specification.

MALCOLM L. COSSITT.
